UNITED STATES PATENT OFFICE.

THOMAS SPENCER, OF PHILADELPHIA, PENNSYLVANIA, ASSIGNOR TO THE HELIOS UPTON COMPANY, OF SAME PLACE.

ELECTRIC-ARC LAMP.

SPECIFICATION forming part of Letters Patent No. 655,526, dated August 7, 1900.

Application filed May 14, 1900. Serial No. 16,554. (No model.)

To all whom it may concern:

Be it known that I, THOMAS SPENCER, of Philadelphia, in the State of Pennsylvania, have invented certain new and useful Im- 5 provements in Electric-Arc Lamps, whereof the following is a specification, reference being had to the accompanying drawings.

My invention relates particularly to a dash-pot forming part of the regulating mechanism 10 of an arc-lamp and so arranged with respect to the lamp-carbon and the regulating-solenoid that its braking effect serves to prevent excessive movement of said carbon from sudden fluctuations in the magnetic field of said 15 solenoid, which fluctuations may occur at any time during the practical operation of the lamp, and particularly at each beginning of such operation.

The dash-pots ordinarily provided for the 20 purpose described are of either one of two general types, whereof the first comprises a cylindrical chamber and a piston loosely fitted therein, so arranged that the movement of the lamp-carbon in both directions of its re- 25 ciprocation is checked or retarded in accordance with the rate of leakage of air around said loose piston. The second type aforesaid comprises in addition to the piston and piston-chamber a valve so arranged that the 30 braking action of the device is constant in the direction of reciprocation of the lamp-carbon opposed to the pull of the solenoid. The first type of dash-pot aforesaid is only useful during the abnormal regulation of the 35 lamp and is a hindrance to the normal regulation of the lamp, because its full braking effect is constant and opposed to every regulating movement of the lamp-carbon. The second type of dash-pot aforesaid is objection- 40 able in that the braking effect is constant in the one direction and opposed to the normal regulation of the lamp.

My invention comprises a dash-pot so constructed and arranged that the full braking 45 effect thereof is automatically secured in opposition to any sudden movement of the lamp-carbon; but, as hereinafter set forth, the relation of the parts of the device is such that no braking effect whatever is opposed to the 50 normal regulation of the lamp. Therefore a more efficient regulation is secured by my in-

vention under both abnormal and normal conditions of operations than has been possible with the devices hitherto known.

Although my improvements are applicable 55 to any form of arc-lamp, they are of particular advantage in connection with an inclosed arc-lamp energized by an alternating circuit, and therefore I have shown such embodiments of my invention in the accompanying 60 drawings, wherein—

Figure 1 is an elevational view, partly in section, showing a convenient form of my invention. Fig. 2 is a view similar to Fig. 1, showing a modified form of my invention. 65 Fig. 3 shows the application of my improvements to an arc-lamp wherein the movable core-armature of the regulating-solenoid is fixed to the carbon-holder, so as to directly shift the latter. Fig. 4 is an enlarged view 70 of the form of dash-pot shown in Fig. 1. Fig. 5 is a sectional view taken on the line A A in Fig. 4. Fig. 6 is a view similar to Fig. 4, showing a modified form of spring for the valve. Figs. 7 and 8 show modified forms of 75 valve mechanism.

Referring to Figs. 1 and 4, 1 is the frame of the lamp, upon which is fixed the regulating-solenoid 2, provided with the movable core-armature 3. 4 is a dash-pot plunger or piston which is fixed upon said frame, and the dash-pot cylinder 5 is mounted for vertical reciprocation with respect to said piston. 6 is an air-port extending from the interior of said cylinder to the atmosphere, and 7 is a 85 valve adapted to close said port. Said valve is provided with a stem 8, extending through said port, and 9 is a spring arranged to normally maintain said valve open. Said solenoid 2 is operatively connected with said dash- 90 pot by means of the lever 10, which is fulcrumed upon the frame 1 at 11 and pivotally connected with the armature 3 at 12 and with the valve 7 at 13.

14 is a clutch of any convenient form operatively connected with the lever 10 by the link 15 and arranged to serve as a holder for the movable carbon 16, which in the form of lamp illustrated is opposed to the carbon 17 within the translucent inclosure 18. 100

As best shown in Fig. 4, the bearing-surface of the valve 7 is preferably spherical, so

that the same may be readily seated whether the parts are in precise alinement or not. Although I prefer to normally maintain said valve 7 open by means of a spring 9 of the 5 form best shown in Fig. 5, it is obvious that a spring of any other configuration may be employed. For instance, I have shown in Fig. 6 an ordinary wire spiral spring 19, which bears at its upper extremity upon the wall of 10 the chamber 5 and at its lower extremity upon the flange 20 of the valve 21.

Although I prefer to provide the dash-pot with a spring-actuated valve, as above described, the spring may be dispensed with, as 15 shown in Figs. 2 and 7, wherein a valve-chamber 22 is provided intermediate of the length of the port 6 to receive the spherical valve 23, which is arranged to seat at 24 and close said port 6 whenever the air is caused 20 to rush into the port 6 by sudden upward movement of the dash-pot cylinder 5, the normal position of said valve being that shown in said Figs. 2 and 7, wherein the valve is open and the interior of the cylinder 5 is in 25 communication with the outer atmosphere, the weight of said valve serving to restore it to its normal position when relieved of the sudden rush of air through the port 6.

In Fig. 8 the valve 25, which is similar in 30 form to that shown in Figs. 1, 4, and 6, is provided with counterweight-levers 26, which are connected with the cylinder 5 by means of links 27 and are so proportioned as to normally maintain the valve in open position, as shown.

In the form of my invention shown in Fig. 3 the regulating-solenoid 2 and the armature 3 are in concentric relation with the carbon 16 and the valve 28 is directly connected 40 with said armature 3 by means of the extension 29. The valve 28 is arranged to be seated within the piston 30; but the spring 31 serves to normally maintain said valve open. Said piston 30 and the cylinder 32, with 45 which it coöpates, are in concentric relation with the solenoid and its core, said cylinder being in fixed relation with the frame 1 and said piston being movable with respect to said frame.

50 The operation of my invention is the same in the various forms hereinbefore described, to wit: The parts are so related that the ordinary regulating movements of the carbon-holder in correspondence with fluctuations 55 in the magnetic field of the solenoid are effected by means operatively connecting said solenoid with the holder of the movable carbon and accompanied by merely idle movement of the dash-pot, without any braking 60 action of the latter, for the reason that the valve-spring or equivalent means described serve to maintain said dash-pot valve open and permit air to pass freely in or out of the port. However, any sudden fluctuation in 65 the magnetic field of the solenoid, occasioned by any abnormal condition of the lamp-circuit, results in such sudden initial movement

of the armature and of the dash-pot elements connected therewith as to close the valve of the dash-pot and by sealing the latter instantly oppose the pressure of the atmosphere to such abnormal movements. Any such abnormal movement of the regulating mechanism being thus instantly checked by the braking action of the dash-pot, the valve of the 70 latter immediately assumes its normal position under the operation of the spring or other means provided to maintain said valve 75 normally open.

It is to be noted that the above-described 80 arrangement and operation of my invention are such that my improved dash-pot is thrown into and out of operation automatically and is only in operation to produce a braking effect upon the regulating mechanism when 85 the latter has a tendency to abnormal movement, the operation of my invention being such as to instantly check the abnormal movements of the regulating mechanism and yet leave the latter free to respond with 90 precision to the minute fluctuations in the magnetic field of the regulating-solenoid, which occur from instant to instant during the normal regulation of the lamp. Therefore my invention is advantageous, as above 95 described, in that a more precise regulation of the lamp may be secured under all conditions of its operation and with a minimum expenditure of energy to effect such regulation.

I do not desire to limit myself to the precise 100 details of construction which I have shown, as it is obvious that they may be varied in accordance with the particular lamp structure in which the regulating mechanism is embodied without departing from the spirit 105 of my invention.

I claim—

1. In an electric-arc lamp, the combination with a regulating-solenoid, of a carbon-holder, a dash-pot operatively related to said solenoid, and means arranged to prevent the braking action of said dash-pot during the normal movement of said carbon-holder, and to automatically secure the braking action of said dash-pot by sudden movement of said carbon-holder, substantially as set forth.

2. In an electric-arc lamp, the combination with a regulating-solenoid, of a movable armature for said solenoid, a carbon-holder, a dash-pot operatively related to said armature, and to said carbon-holder, and means arranged to prevent the braking action of said dash-pot during the normal movement of said armature, and to automatically secure the braking action of said dash-pot by sudden movement of said armature, substantially as set forth.

3. In an electric-arc lamp, the combination with a regulating-solenoid, of a movable armature for said solenoid, a dash-pot, comprising a cylinder and piston arranged for relative reciprocation, means operatively connecting said armature and said dash-pot, an air-port between the interior of said dash-pot and the outer atmosphere, a valve arranged to control

the passage of air through said port, means in operative relation with said valve arranged to normally maintain said port open, and means arranged to close said port by sudden 5 movement of said armature, substantially as set forth.

4. In an electric-arc lamp, the combination with a regulating-solenoid, of a movable armature for said solenoid, a carbon-holder, a dash-10 pot, comprising a cylinder and piston in relatively-movable relation, an air-port between the interior of said dash-pot and the outer air, a valve arranged to control the passage of air through said port, a lever operatively connecting said armature, said carbon-holder and said valve, and a spring arranged to normally maintain said valve open, substantially 15 as set forth.

5. In an electric-arc lamp, the combination 20 with a frame, of a regulating-solenoid fixed

upon said frame, a dash-pot piston fixed upon said frame, an armature arranged to reciprocate in said solenoid, a dash-pot cylinder arranged to reciprocate on said piston, an air-port extending through the wall of said cylinder, a valve arranged to close said port, and provided with a stem, extending therethrough, a lever fulcrumed on said frame and pivotally connected with said armature and said valve-stem, a carbon-holder connected with 25 said lever in opposition to said armature, and a spring within said cylinder arranged to normally maintain said valve open and to permit the closure of said valve by sudden movement of said armature, substantially as set forth. 30 35

THOMAS SPENCER.
